UNITED STATES PATENT OFFICE.

ARTHUR A. PIEPJOHN, OF CHICAGO, ILLINOIS.

ELECTRIC DECORTICATOR.

Application filed July 27, 1923. Serial No. 654,155.

To all whom it may concern:

Be it known that I, ARTHUR A. PIEPJOHN, a citizen of the German Republic, residing at Chicago, in the county of Cook and State 5 of Illinois, have invented certain new and useful Improvements in an Electric Decorticicator, of which the following is a specification.

This invention relates to improvements 10 in electrically operated machines or apparatus for removing by agitation and abrasive action the peel, skins, or cortex of vegetables, fruit and the like, and it consists in certain peculiarities of the construction, 15 novel arrangement and combination of the various parts thereof as will be hereinafter more fully set forth and specifically claimed.

While the principal object of the invention 20 is the provision of an electric agitator or vibrator combined with other elements of the device, whereby a potato peeler, or a machine for the quick peeling or removal of the skins of potatoes without undue waste 25 of the bodies thereof will be furnished, yet which device can be employed for the removal of the skins or peel of various kinds 30 of vegetables and fruit, such as turnips, carrots, parsnips, radishes, cucumbers, apples, pears, and the like.

A further object of the invention is to so construct and arrange the parts of the apparatus that an electric motor of the ordinary or standard construction may be and 35 usually is employed as one of the elements of the device, thereby obviating the expense of employing a motor of special construction or altering the construction of those of the standard make.

Still another object is to so construct and 40 arrange the parts of the mechanism, that vibration of the motor in producing the necessary vibration or agitation in the machine will be reduced to a minimum or practically eliminated, thereby reducing the wear 45 and tear of the motor.

Other objects and advantages of the invention will be disclosed in the following description and explanation.

In the accompanying drawings, which 50 illustrate an embodiment of the invention,—

Figure 1 is a plan view of the device.

Fig. 2 is a front view in elevation thereof.

Fig. 3 is a central sectional view taken 55 on line 3—3 of Fig. 1 looking in the direction indicated by the arrows.

Fig. 4 is an enlarged vertical sectional view of a portion of the upright support for the motor and frame of the device, showing a fragment of the vibratory container, and 60 means connecting said container to the motor for imparting vibratory movement thereto.

Like numerals of reference refer to like parts throughout the different views of the 65 drawing.

The support of the device comprises a base 7 having extended upwardly from its central portion a hollow upright 8 which may be provided with a door-way and door 70 9 for closing the same, which door-way may be employed for giving access to the motor 10 which is suitably mounted in the casing or upright 8 with its shaft disposed vertically as shown. 75

Extended horizontally and radially from the upper portion of the upright 8 are a plurality, usually three, tubular members 10^a, each of which has connected to its outer end by a suitable coupling 11, an upwardly 80 and vertically extended tube 12 each of which has connected to its upper end by means of a suitable coupling 13 a tube 14 which are extended inwardly to a point directly above the axial line of the shaft of the motor and are connected together at 85 their adjacent or inner ends by means of a three-way coupling 15 as will be readily understood by reference to Fig. 1 of the drawings. As shown in Fig. 3, one of the vertical or upright members 12 is extended upwardly to a greater extent than the other members 12 and that its connecting member 14 which unites it to the coupling 15, is located horizontally instead of being inclined 90 as are the other two members 14 of the frame. 95

While I have shown the members 10^a, 12 and 14 as being tubular in each instance and prefer to so make them on account of lightness, yet, it will be understood that they can be of any suitable construction or shape. 100

Mounted on a suitable bracket 16 at the juncture of one of the members 12 and one of the members 14, is an electric switch 17 of the ordinary or any well known construction, from which switch conductors 18 are extended through one of the hollow tubular members 12 and one of the horizontal members 10^a to the motor. The switch 17 is electrically connected through a conductor 19 105 with a source of electricity, not shown. Sus- 110

pended from the apex of the supporting frame or from the coupling 15 thereof by means of a flexible connection such as a chain 20, is a vibratory container which is designated as a whole by the reference numeral 21 and consists of a cylindrical portion 22 having a bottom or closure provided with an outlet 23 which may be in the form of a depending spout as shown in Fig. 2 10 of the drawings. This outlet is preferably located near the periphery of the cylindrical portion 22 and is employed for the purpose of discharging water and sediment which may collect in the container into a bucket 24 mounted on the base 7 of the support or to any other suitable point. The cylindrical portion 22 of the container 21 is provided in its wall with a door-way and door 25 therefor which can be used for the 15 removal of the articles held by the container after they have been peeled or have had their skins or peeling removed.

Located within the cylindrical portion 22 of the container 21 and held in spaced relation thereto by means of suitable studs or brackets 26 extended upwardly from the bottom of the cylindrical portion 22 and inwardly from its walls, is a reticulated or foraminated receptacle which is designated 20 as a whole by the reference numeral 27 and by preference is of substantially the same shape as the part 22 of the container 21. As shown in the present instance, the receptacle 27 has its cylindrical portion or walls made 25 of reticulated material or netting, while its bottom is made of sheet metal and provided with upwardly extended tubular projections 28 which are spaced apart and form an abrasive or grating surface upon which the 30 articles to be peeled will rest, as well as orifices through which water and the grated peelings may pass.

Mounted on the upper end of the cylindrical portion 22 of the container 21 and secured thereto by means of bolts 29 and nuts 30, is the lower end or rim of a conical shaped cover 31 for said container. The apex of the cover 31 is secured to the lower end of the chain or flexible connection 20 in such a way that the container 21 may have free movement in all directions. The cover 31 is provided with a door-way and door 32 therefor through which door-way the articles to be peeled may be passed into 35 the container. Mounted within the container 21 near its tapered upper portion is a perforated water discharging device or sprayer 33 which has communication through a pipe 34 with a supply of water, 40 not shown.

Centrally mounted on the bottom of the cylindrical portion 22 of the container 21 is a ball bearing designated as a whole by the numeral 35 one of the races or ball retaining members 36 of which is fixed to the

bottom of said container, while the other race or ball retaining member 37 is fixedly secured to the upper end of a short shaft 39 on the lower portion of which is mounted to rotate therewith a wheel or disk 40 70 which is provided with an over-balance or weight 41 shown in Figs. 2 and 4 of the drawings. Fixedly secured to the shaft 39 below the wheel or disk 40 by means of a clamp 42 and screws 43 is the upper end of 75 a coil spring 44 which spring extends downwardly into the upper portion of the upright casing 8 of the support and is fixedly secured at its lower end by means of a clamp 45 and screws 46 to the shaft 47 of the motor. By this arrangement it will be obvious that in the rotation of the motor shaft rotary movement will be conveyed therefrom through the spring 44 to the shaft 39 and the wheel 40 thereon, and that by reason of 80 the fact that the wheel 40 is over-balanced or weighted, gyroscopic movement of the same and its shaft will be created to the end that, the container 21 through its connection with the shaft 39 through the ball bearing, will 85 be rapidly or vigorously vibrated.

The operation of the device is simple and as follows:

Potatoes or other articles to be peeled may be placed in the receptacle 27 of the vibratory container by opening the door 32 in the cover of said container. If desired, water may be sprinkled on the potatoes or articles by means of the sprayer 33, when by turning the switch 17, current may be supplied to the motor, thus causing the same to operate and through the instrumentality of the transmission means between the shaft 47 of the motor and the bottom of the vibratory container cause the latter to be vibrated very rapidly and with such force as to subject the articles held by the container to substantially constant movement and change of positions, thus bringing all parts of each of the articles in rubbing contact with the abrasive receptacle 27 carried by the vibratory member or container.

In the above mentioned operation, the skins or peel will be removed from the articles in such a way that very little waste of the bodies of the articles will be produced. While I have shown in the drawings the receptacle 27 as having reticulated walls or walls of netting which may be roughened in any suitable manner, and with a grate-like bottom, yet I do not desire to be limited in the construction of this receptacle, as it may be made of any suitable abradant material and provided with perforations for the passage of water and sediment, said perforations being located either in the wall of the receptacle or in its bottom, or in both parts. The receptacle 27 is securely held in position by the studs or brackets 26 on the container, but if desired, it can be removed by 130

disconnecting the cover 31 from the cylindrical portion 22 of the container by simply removing the bolts 29 and nuts 30 which serve to hold said parts together.

5 Having thus fully described my invention, what I claim as new and desire to secure by Letters Patent is:—

1. In a device of the class described, the combination with a vibratory member supported for free movement in any direction, of a shaft connected to said member for independent rotation and extended therefrom, an over-balance or weight carried by said shaft, an electric motor mounted near said member with its shaft disposed axially with respect to the point of support of said member, and a flexible connection uniting said shafts.

2. In a device of the class described, the combination with a vibratory member supported for free movement in any direction, of a shaft connected to said member for independent rotation and extended therefrom, an over-balance or weight carried by said shaft, an electric motor mounted near said member with its shaft disposed axially with respect to the point of support of said member, and a coil spring fixed at one of its ends to the motor shaft and fixed at its other end to the shaft carried by said member.

3. In a device of the class described, the combination with a vibratory container supported for free movement in any direction, of a shaft connected to said container for independent rotation with respect thereto and extended therefrom in alignment with the point of support of the container, an over-balanced disk on said shaft, an electric motor mounted near said container with its shaft disposed in substantial alignment with the shaft of the container, and a flexible connection uniting the adjacent ends of said shafts.

4. In a device of the class described, the combination with a vibratory container supported for free movement in any direction, of a shaft connected to said container for independent rotation with respect thereto and extended therefrom in alignment with the point of support of the container, a disk mounted on said shaft, an over-balancing weight on said disk, an electric motor near said container with its shaft disposed in substantial alignment with the shaft of the container but spaced from the latter named shaft, and a coil spring fixed at one of its ends to the motor shaft and fixed at its

other end to the adjacent end of the shaft carried by said container.

5. In a device of the class described, the combination with a vibratory container supported for free movement in any direction, of a receptacle located in said container and having abradant means on its inner surface, a shaft connected to said container for independent rotation with respect thereto and extended therefrom at a point opposite the point of support of said container, a disk mounted on said shaft, an over-balancing weight on said disk, an electric motor mounted near said container with its shaft disposed in substantial alignment with the shaft of the container but spaced from the latter named shaft, and a coil spring fixed at one of its ends to the motor shaft and fixed at its other end to the adjacent end of the shaft carried by said container.

6. In a device of the class described, the combination with a base having a hollow upright, a frame mounted on the upper portion of said upright and comprising a plurality of upwardly and inwardly extended members joined together at their upper ends directly above the said upright, a vibratory container flexibly supported at its upper portion on the overhanging portion of said frame, a shaft connected to said container for independent rotation with respect thereto and extended therefrom at a point directly below the point of support of the container, a disk mounted on said container, an over-balancing weight on said disk, an electric motor mounted within said upright with its shaft disposed in substantial alignment with the shaft of the container but spaced from the last named shaft, and a coil spring fixed at one of its ends to the motor shaft and at its other end to the adjacent end of the shaft carried by said container.

7. In a device of the class described, the combination with a vibratory container supported for free movement in any direction, of abradant means located within said container, a ball bearing mounted on the bottom of the container with one of its race-ways fixed thereto, a shaft fixed at one of its ends to the other race-way of said bearing, a disk mounted on said shaft below said bearing, an over-balancing weight on said disk, an electric motor mounted near and below said container, and a coil spring fixed at one of its ends to the motor shaft and fixed at its other end to the adjacent end of the shaft carried by the container.

ARTHUR A. PIEPJOHN,
